[57] CLAIM

The ornamental design for a computer chassis for selecting paint products and tint formulations, as shown and described.

DESCRIPTION

FIG. 1 is a top perspective view of a computer chassis for selecting paint products and tint formulations showing our new design;

FIG. 2 is a top plan view of our design as shown in FIG. 1 on an enlarged scale;

FIG. 3 is an elevation view of one side of our design;

FIG. 4 is an elevation view of the side opposite the side shown in FIG. 3 of our design;

FIG. 5 is an elevation view of one end of our design;

FIG. 6 is an elevation view of the end opposite the end shown in FIG. 5;

FIG. 7 is a top plan view of a second embodiment of our design, the undisclosed views are similar in appearance to those of the first embodiment; and,

FIG. 8 is a bottom plan view of our design as shown in FIGS. 1-7 the broken lines show recesses for receiving means to attach the computer chassis to a wall, and legs and leg recesses, and are for illustrative purposes only and form no part of the claimed design.

FIG. 1

FIG. 2
